UNITED STATES PATENT OFFICE

LYTLE GALE HUNTER AND HARRY B. REISIGER, OF FLUSHING, NEW YORK, ASSIGNEES
TO THE HUNTER ILLUMINATED CAR SIGN COMPANY, OF FLUSHING, NEW YORK,
A PARTNERSHIP COMPOSED OF LYTLE J. HUNTER, FENLEY HUNTER, AND GALE
HUNTER

INDICATOR

Application filed April 12, 1930. Serial No. 443,726.

This invention relates to a novel and improved form of indicator, particularly of the type used in subway trains, street cars, and the like. The novel features will be best understood from the following description and the annexed drawings in which are shown certain selected embodiments of the invention and in which:

Fig. 1 is a face view of the indicator as seen, for example, from the outside of a car in which the indicator is installed.

Fig. 2 is a section on the line 2—2 of Fig. 1, part of the car wall being shown.

Fig. 3 is a view of the indicator as seen from the interior of a car with which it may be used.

Fig. 4 is a section on the line 4—4 of Fig. 3.

Fig. 5 is a fragmentary view of a form of web forming part of the invention.

Fig. 6 is a longitudinal horizontal section through one of the boxes shown in Fig. 2.

Fig. 7 is a section on the line 7—7 of Fig. 6.

Fig. 8 is a face view of the novel form of bearing for supporting the ends of the shafts carrying the rolls.

Fig. 9 is a plan view of the structure shown in Fig. 8.

Fig. 10 is a view on the same plane as Fig. 2, showing a modified arrangement of boxes with respect to the lighting means therefor.

Fig. 11 is an elevation taken at right angles to Fig. 10, and showing the same modification.

Fig. 12 is a view of the novel form of web which may be used with our indicator.

Fig. 13 is a wiring diagram showing how a plurality of indicators may be controlled together.

Referring first to Figs. 1 and 2, the indicator comprises a casing 1 which may be secured in any desired manner in a car, the wall of which is indicated at 2. According to one feature of this invention, the route is continually shown by one sign, here shown as a web 3 mounted on rolls 4 disposed on opposite sides of windows 5 and 6 in the lower part of the casing 1. The window 5

exposes the web to view on the outside of the car, whereas the window 6 exposes it to view on the interior of the car. The web may be used to contain a plurality of route designations and the rolls may be operated by a handle 7 through gearing, not shown, in the usual way. The windows 5 and 6 not only expose the web to view but also provide light for illumination. It is, of course, understood that this web is opaque and has route designations on opposite sides thereof so arranged that the same designation is given simultaneously through both windows 5 and 6.

Supported in the casing as on shelves 8, is a box 9 having an opening 10 in the bottom thereof through which may project a socket 11 adapted to receive an electric lamp 12. The box is provided with openings 13 and 14 disposed on opposite sides of the box and with a closed top 15. The casing is provided with windows 16 and 17 registering respectively with the openings 13 and 14.

In the box 9 is a sign in the form of a web 18 mounted on rolls 19 and 20 in the lower part of the box adjacent the lower corners. This web is carried upwardly past the openings 13 and 14 and over idler rolls 21 in the upper corners of the box.

As best shown in Fig. 5, the web 18 carries terminal designations 22 and 23. The two designations 22 are the same, except that they are arranged in a pair with the two designations in the pair spaced longitudinally of the web and at such a distance that when one of these designations is exposed through the opening 14 and the window 17, the other designation of the pair will be exposed through the opening 13 and window 16. The same holds true of the designations indicated at 23. By this arrangement, it will be seen that similar designations are exposed simultaneously from the same web at windows on the inside and outside of the car. The lamp 12 is disposed between these two designations so that it serves the purpose of illuminating both of them simultaneously, it being understood that the designations are translucent. By this we mean that the characters forming the designations may be translucent and their background opaque, or vice versa.

Supported on the box 9 is a second box 24 having a closed bottom 25 resting upon the closed top 15 of the box 9. The top of the box 24 is provided with an opening 26 through which depends a lamp 27 secured in a socket 28 in the top of the casing. This lamp 27 is provided with a neck 29 of such a length that the socket 28 need not extend into the box 24. By this arrangement the box 9 may be placed in the casing first, the opening 10 in its bottom receiving the socket 11.

The web 18 has preferably adjacent each end thereof, a hand hole 18a (Fig. 5) through which the lamp 12 may now be inserted in the socket 11. In case a plurality of lamps are used, a hand-hole may be provided for each lamp, or one hand-hole may be used to insert several lamps, as desired.

After the box 9 is in place, the box 24 may be slid into position on top thereof, as indicated in Fig. 2. Then the lamp or lamps 27 may be placed in their respective sockets 28 by inserting them through one of the openings 30 or 31 in the box 24 and through a handhole in the web 18', this web being provided with handholes similar to those just described above in connection with the web 18. Here, again, the number of lamps and handholes may be varied to suit various conditions.

It is, of course, understood that the vehicle on which the indicator is used will usually travel in opposite directions over a certain route. There may be different terminals for the vehicle in either direction of travel. For example, if the route is one running north and south, it may be that when the vehicle is traveling north over its route, there are several terminals, any one of which may be used as the end of its northbound trip. Similarly, of course, for its southbound trip, any one of a number of different terminals may be adopted. Therefore, we preferably place on one web 18, designations of all the terminals for the vehicle when traveling in one direction, and on the other web 18' we place designations of all the terminals for the vehicle when traveling in the opposite direction.

The casing has windows 32 and 33 registering with the openings 30 and 31 respectively, and the box 24 carries a web 18' corresponding to the web 18 in all essentials. In this box, however, the web is mounted on rolls 20' supported in the top of the box, and the web runs over idlers 21' in the bottom corners of the box. Otherwise, the arrangement is identical with what is used in the box 9.

Each web is operated by a handle 34, Figs. 3 and 6, through suitable gearing indicated generally by the numeral 35 in Figs. 6 and 7. The details of this gearing may be varied, as desired, and need not be further described.

At the windows 16, 17, 32 and 33, there is

preferably shown the word "to" which may be accompanied by an arrow, as shown in Figs. 1 and 3, for the purpose of indicating to a passenger the terminal toward which the train or car is traveling. These designations may be permanently affixed to the windows or may be placed on separate webs, as indicated at 35 in Fig. 6. The windows 16 and 32 are mounted in a door 36 which may be hinged at 37 and provided with a suitable latch 38, thereby giving access to the upper part of the casing. A similar door 39 may be provided for the lower part of the casing to give access to the web 3 and associated parts.

By the arrangement shown and described, it is possible to have a continuous indication of a route over which a car travels. It is also possible to have opposite terminals designated on the webs 18 and 18', respectively, once and for all, and then to illuminate the terminal designation toward which the car is traveling, leaving the other terminal designation darkened by turning off the light which is provided for illuminating it. In this manner there is avoided the uncertainty and the loss of time involved in previous arrangements by which the trainmen were required to change each individual sign. Often such change is not made at all or is improperly made. With our invention, the two terminal designations and the route are properly displayed at the beginning of the day or other period of time during which the car is to be used on a certain route. Then, at the beginning of the first trip the lamp or lamps behind the designation of the terminal toward which the car is moving is lighted, and the lamp behind the other terminal designation is turned off. At the end of the trip the illumination of the terminal designations is reversed. This operation need not require the attention of individual trainmen but may be operated by the motorman in charge of an entire train. For example, Fig. 13 shows a wiring diagram in which are graphically indicated the webs 18 and 18' in a plurality of cars. In this diagram one lamp is shown for each web, although in the other figures of the drawings two lamps are shown for each web, this obviously being a matter of design. The lamps 27 may be connected in parallel to a source of energy 40, and the lamps 12 may similarly be connected to the same source, and then all the lamps 27 and all the lamps 12 may be alternately illuminated by the operation of a two-way switch 41. This switch may conveniently be located at the motorman's station, so that he may operate the lights on the entire train.

Referring now to Figs. 6, 7, 8 and 9, and particularly to Fig. 6, we have shown the rolls 20 as provided at their ends with shafts 42 received within bearings 43 which will be more fully described presently. These bear-

ings are fixed on the wall of the box so that the axis of the roll shaft is also fixed.

Each roll is provided adjacent its end with a disk 44 cooperating with a friction disk 45 having a hole through which the shaft 42 passes. A plate 46 carries and bears against both of the disks 45 which are disposed substantially in a common plane, and any force exerted by the friction disk is governed by a spring 47, the tension of which may be controlled by an adjusting screw 48. By this arrangement the tension on the web is maintained at a desired amount and, at the same time, the bearings for the roll shafts are fixed. It has been common in prior art constructions to have these bearings movable but, according to our invention, this is avoided, and at the same time an efficient tension device is provided.

Referring now more particularly to Figs. 8 and 9, it is seen that the bearings 43 comprise two parallel fixed members 49 which are here shown as loops in a one-piece metallic plate. These two fixed members form two opposite sides of the bearing, and the other two sides are formed by the legs 50 and 51 of a U-shaped bar. This bar passes through holes in the members 49 and the leg 51 is seen to be shorter than the leg 50, so that upon movement of the bar toward the left, as viewed in Figs. 8 and 9, the end of the leg 51 will move out of the way so that the shaft 42 may be removed. A spring 52 bearing between one of the members 49 and a head 53 of the leg 50 normally retains the bar in operative position to secure the shaft in place.

In Figs. 10 and 11 we have shown a modification of the arrangement for mounting the lamps to illuminate the webs 18 and 18'. In this form the lamps 12 and 27 are mounted in sockets which are supported on a flexible member 54 which is hinged at 55 adjacent one end of the casing between the boxes and latched at 55', the lamps and sockets projecting through openings therein. By this arrangement, each box 9' and 24' may be independently supported in the casing and the member 54 may be flexed one way or the other, as is necessary to get the lamp sockets out of the way when the boxes are being inserted.

In Fig. 12, we have shown a web 56 having terminal designations 57 and 58 thereon arranged with respect to each other in the same way as indicated in Fig. 5. In this form, however, the sheet is white on the side which is exposed to the reader. The other side is coated with some substance which renders the web opaque, it being of course understood that the web is made of the usual cloth which is translucent. On the reverse of the web which is thus coated, the desired letters or characters are formed by omitting the coating. In other words, the characters are formed by portions of the translucent web itself and the

background for the letters is formed by the relatively opaque coating. This coating may be of any suitable material but we have found that an ink may be formed of powdered aluminum and varnish, which will give the desired results. This gives a background of the color of aluminum or silver and when there is no light behind the web the front or uncoated part appears substantially all white, although the letters may be discerned by a close inspection. Upon turning on of a lamp behind this web the letters or other characters stand out prominently.

While we have shown the invention as embodied in a specific form, it is to be understood that various changes in details may be made without departing from the scope of the invention, and we therefore do not intend to limit ourselves except by the appended claims.

We claim:—

1. An indicator comprising three signs, one indicating a route and the other two indicating opposite terminals of said route, means for continually illuminating the route sign, and means for alternately illuminating said terminal signs.

2. An indicator comprising three webs forming signs, one of said webs being opaque and having a route designation on both sides thereof, means for illuminating both of said sides, the other two webs being translucent and having terminal designations thereon, and means for alternately illuminating said two webs.

3. An indicator comprising three webs forming signs, one of said webs being opaque and having a route designation on both sides thereof, means for illuminating both of said sides, the other two webs being translucent and having terminal designations thereon at a plurality of spaced points, and means for alternately illuminating said two webs at said spaced points.

4. An indicator comprising a casing, a web containing route indications thereon, means to support said web in said casing and to move it past an exposure aperture therein whereby different route indications may be exposed at said aperture, means to illuminate the sign exposed at said aperture, two other webs carrying terminal designations corresponding to the route indications on said first-named web, each of said two webs being supported in said casing, and means to move each of said webs past an aperture in the casing.

5. An indicator comprising a box of rectangular cross-section, rolls in two adjacent corners of the box, a web having translucent portions and secured at its opposite ends to said rolls, means to operate said rolls, idler rolls in the other two corners of the box over which said web passes, a lamp within the box and extending between said rolls into

the path of the web over said rolls, a plurality of apertures in the box adjacent said path, and means to turn said lamp off and on.

6. In combination, a plurality of similar indicators each comprising two signs indicating opposite terminals of a route, an electric lamp disposed behind each of said signs and adapted to illuminate the same, and means adapted to light all of the lamps behind the signs indicating one terminal, and to put out the lamps behind the other signs.

7. In an indicator, a roll adapted to carry a web and having a shaft, a bearing for said shaft comprising two fixed members parallel to each other and disposed on opposite sides of the shaft, and two slidable members disposed on opposite sides of the shaft at right angles to said fixed members and one shorter than the other, whereby upon movement of said slidable members said shaft may be released when said shorter member is moved past the shaft.

8. In an indicator, a roll adapted to carry a web and having a shaft, a bearing for said shaft comprising two fixed members parallel to each other, a U-shaped rod extending through holes in said members and adapted to embrace the shaft between opposite legs of the U, said U-member being slidable in said holes and one side of the U being shorter than the other whereby upon sliding movement of the U the shaft may be released.

9. In an indicator, a pair of rolls and a web secured at opposite ends to said rolls, a friction disk on the end of each roll, said disks being disposed substantially in a common plane, shafts on the rolls extending through said disks, fixed bearings receiving said shafts at their ends, friction disks engaging said first-named disks and secured to a common connecting member and having holes through which said shafts pass, said member being disposed between the bearings and said first-named disks, and means resiliently urging said friction disks toward the disks on said rolls.

10. An indicator comprising a casing, two boxes disposed in said casing one above the other, means on the casing to support the lower box and the other box being supported on the lower box, changeable signs in each of said boxes adapted to be displayed at apertures in said casing and box, a lamp socket in the casing and projecting through a hole in the bottom of the lower box, and a lamp socket in the top of the casing so disposed as to permit the upper box to be slid laterally in position on top of the lower box, said upper box having an opening in its top to permit a lamp to be inserted in said upper socket and to depend into said upper box.

11. An indicator comprising a casing, two boxes disposed in said casing one above the other, means on the casing to support the lower box and the other box being supported

on the lower box, changeable signs in each of said boxes adapted to be displayed at apertures in said casing and box, a lamp socket in the casing and projecting through a hole in the bottom of the lower box, and a lamp socket in the top of the casing so disposed as to permit the upper box to be slid laterally in position on top of the lower box, said upper box having an opening in its top to permit a lamp to be inserted in said upper socket and to depend into said upper box and each sign having a hand-hole through which a lamp may be inserted.

12. In an indicator, a casing having an opening in a wall thereof, a web extending across said opening, means to move the web, and a lamp on the other side of the web from said wall, said web having a hand-hole therein through which said lamp may be put in place.

13. In an indicator, two rolls spaced apart, a web having its opposite ends secured to said rolls and having translucent portions to form sign designations on the web, means to operate said rolls together to unwind the web from one roll and wind it on the other, a lamp extending between said rolls, and means to guide the web around the lamp, whereby the lamp may simultaneously illuminate sign designations on opposite sides thereof.

14. In an indicator, two rolls spaced apart, a web having its opposite ends secured to said rolls and having translucent portions, means to operate said rolls together to unwind the web from one roll and wind it on the other, a lamp extending between said rolls, and means to guide the web around the lamp, said web having a hand-hole through which said lamp may be reached from the other side of the web.

15. In an indicator, two similar boxes disposed one above the other and each having a web therein carrying signs, the lower box having an opening in its top and the upper box having an opening in its bottom, a flexible electric conductor disposed between said boxes, lamps connected to said conductor one projecting upwardly into the upper box and the other projecting downwardly into the lower box, and a casing supporting said boxes whereby the lamps may be manipulated first into one box and then into the other to permit insertion of the boxes into the casing.

16. In an indicator, a roll adapted to carry a web and having a shaft, a bearing for said shaft comprising two fixed members parallel to each other and disposed on opposite sides of the shaft, two slidable members disposed on opposite sides of the shaft at right angles to said fixed members and one shorter than the other, whereby upon movement of said slidable members said shaft may be released when said shorter member is moved past the shaft, and a spring resisting said movement to maintain said slidable members in position on opposite sides of the shaft.

17. In an indicator, a roll adapted to carry a web and having a shaft, a bearing for said shaft comprising two fixed members parallel to each other, a U-shaped rod extending through holes in said members and adapted to embrace the shaft between opposite legs of the U, said U-member being slideable in said holes and one side of the U being shorter than the other whereby upon sliding movement of the U the shaft may be released, and a spring resisting said movement and tending to maintain both legs of the U on opposite sides of the shaft. 70
18. In an indicator, a pair of rolls and a web secured at opposite ends to said rolls, a friction disk on the end of each roll, said disks being disposed substantially in a common plane, shafts on the rolls extending through said disks, fixed bearings receiving said shafts at their ends, friction disks engaging said first-named disks and secured to a common connecting member and having holes through which said shafts pass, said member being disposed between the bearings 20 and said first-named disks, and a single spring urging both of said friction disks toward the disks on said rolls. 80
19. In an indicator, a pair of rolls, and a web secured at opposite ends to said rolls, a friction disk on the end of each roll, said disks being disposed substantially in a common plane. Shafts on the rolls extending through said disks, fixed bearings receiving said shafts at their ends, friction disks engaging said first-named disks and secured to a common connecting member and having holes through which said shafts pass, said member being disposed between the bearings 30 and said first-named disks, a single spring urging both of said friction disks toward the disks on said rolls, and means to adjust said spring to vary the friction between said disks. 90
20. In an indicator, a pair of rolls and a web secured at opposite ends thereto, fixed bearings rotatably supporting the ends of said rolls, and a friction brake disposed between and contacting with a bearing on each roll and the adjacent end of said roll. 95
21. In an indicator, a pair of rolls and a web secured at opposite ends thereto, fixed bearings rotatably supporting the ends of said rolls, a friction brake disposed between and contacting with a bearing on each roll and the adjacent end of said roll, and means 40 for adjusting said brakes. 105
22. In an indicator, a pair of rolls and a web secured at opposite ends thereto, fixed bearings rotatably supporting similar ends of said rolls, friction brakes disposed between and contacting with said bearings and the adjacent ends of the rolls, and means for adjusting said brakes in unison. 110
23. In an indicator, a pair of rolls and a web secured at opposite ends thereto, fixed bearings rotatably supporting similar ends 45 of said rolls, friction brakes disposed between and contacting with said bearings and the adjacent ends of the rolls, and means for adjusting said brakes. 120
- of said rolls, friction brakes disposed between said bearings and the adjacent ends of the rolls, said brakes comprising members on the rolls and other members cooperating therewith, and a common support for said other 70 members. 125
24. In an indicator, a pair of rolls and a web secured at opposite ends thereto, fixed bearings rotatably supporting similar ends of said rolls, friction brakes disposed between said bearings and the adjacent ends of the rolls, said brakes comprising members on the rolls and other members cooperating therewith, a common support for said other members, and means for moving said support towards and from the rolls to vary the friction 75 between said members. 130
25. In an indicator, a pair of rolls and a web secured at opposite ends thereto, fixed bearings rotatably supporting similar ends of said rolls, a friction brake disposed between one of said bearings and the adjacent end of one of the rolls, and means resiliently urging said brake into engagement with said adjacent end. 85
26. In an indicator, a casing, a box disposed in said casing and having therein a web extending past an opening in the wall of the box, a lamp socket supported on said casing adjacent said box, and a lamp in said socket and projecting through a hole in the box in position to illuminate said web at said opening. 95
27. An indicator comprising three webs forming signs, one of said webs having a route designation thereon, means for illuminating said designation, the other two webs having terminal designations thereon, and means for alternately illuminating said terminal designations. 100
28. An indicator comprising designations of a route and of the terminals of said route, means for continually illuminating said route designation, and means for alternately illuminating the designations of the opposite 110 terminals of the route. 110
29. In an indicator for a vehicle traveling in opposite directions over a route, two webs, one web having a plurality of designations naming different terminals for the vehicle 115 when traveling in one direction over said route and the other web having a plurality of designations naming different terminals for the vehicle when traveling over the route in the opposite direction, means associated with each web to expose the designation of a single terminal thereon at a time, and means to operate each web to bring selected designations into view. 120
30. In an indicator for a vehicle traveling in opposite directions over a route, two webs one web having a plurality of designations naming different terminals for the vehicle when traveling in one direction over said route and the other web having a plurality 125 130 135

of designations naming different terminals for the vehicle when traveling over the route in the opposite direction, means associated with each web to expose the designation of a single terminal thereon at a time, means to operate each web to bring selected designations into view, and means to alternately illuminate the exposed designations on said webs.

10 31. An indicator comprising a box having rolls therein, a web having translucent portions and secured at its opposite ends to said rolls, said box having a wall with an opening in one side thereof, a lamp projecting through said opening into the box, means to guide the web around said lamp during its passage from one roll to the other, and a flexible electric conductor connected to said lamp and extending parallel to the side 15 20 of the box having the opening therein, whereby the conductor may be manipulated to place the lamp in the box or to remove it therefrom.

32. An indicator comprising a web having a plurality of designations thereon, said designations being formed by translucent portions of the web, with the rest of the web forming a background therefor, said background being opaque and of a color approximating that of the color of the translucent portions, and a lamp to pass light through said translucent portions, whereby, when said lamp is turned on, said translucent portions will stand out against the background, while, 25 30 35 when the lamp is turned off, the contrast between the background and the translucent portions is substantially removed.

33. In an indicator, a casing, a box disposed in said casing, a web disposed in said box and movable past an opening in the wall thereof, means to removably support said box in said casing, and a lamp supported on said casing in position to illuminate said web at said opening, said box with the web there- 40 45 in being removable from said casing as a unit.

34. An indicator comprising a web having relatively translucent and opaque portions so arranged with respect to each other as to define the boundaries of predetermined characters, the colors of said translucent and opaque portions being so related to each other that said characters become visible when illuminated by light from the back of the web and becomes substantially invisible when illuminated entirely by light from the front of the web.

35. An indicator comprising a web having relatively translucent and opaque portions so arranged with respect to each other as to define the boundaries of predetermined characters, said translucent and opaque portions having substantially the same color as viewed from the front of the web, whereby 50 55 60 65 70 75 80 85 90 95 100 105 110 115 120 125 130 said characters become visible when illumi-

nated by light from the back of the web and become substantially invisible when illuminated entirely by light from the front of the web.

36. An indicator comprising a web of light-colored translucent material, portions of said web being coated with an opaque light-colored substance and other portions being left uncoated and translucent, said opaque and translucent portions being so arranged with respect to each other as to define the boundaries of predetermined characters and the colors of said translucent and opaque portions being so related to each other that said characters become visible when illuminated by light from the back of the web and become substantially invisible when illuminated entirely by light from the front of the web.

37. An indicator comprising a web of light-colored translucent material, portions of said web being coated on its back with an opaque light-colored substance and other portions being left uncoated and translucent, said opaque and translucent portions being so arranged with respect to each other as to define the boundaries of predetermined characters and the colors of said translucent and opaque portions being so related to each other that said characters become visible when illuminated by light from the back of the web and become substantially invisible when illuminated entirely by light from the front of the web.

CERTIFICATE OF CORRECTION.

Patent No. 1,879,265.

September 27, 1932.

LYTLE GALE HUNTER ET AL.

It is hereby certified that error appears in the printed specification of the above numbered patent requiring correction as follows: Page 3, lines 129 and 130, claim 5, strike out the words "the box and extending between said rolls into"; and in line 129, after the word "lamp" insert the words extending between said rolls into the box and; and that the said Letters Patent should be read with this correction therein that the same may conform to the record of the case in the Patent Office.

Signed and sealed this 15th day of November, A. D. 1932.

(Seal)

**M. J. Moore,
Acting Commissioner of Patents.**
